UNITED STATES PATENT OFFICE.

LAURENCE E. TOPHAM, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

EDGE-TRIMMING MACHINE.

Application filed February 2, 1920, Serial No. 355,820. Renewed May 27, 1925.

This invention relates to shoe machines and more particularly to machines for operating upon shoes of the type in which the shoe and the means for operating upon the shoe are moved relatively to transfer the point of operation about the shoe and in which mechanism is provided for relatively moving the operating means and the shoe to maintain the operating means and the shoe in the proper relative positions at the point of operation as such point is transferred about the shoe.

The invention is illustrated in the present application as embodied in an automatic machine for trimming the edges of shoe soles. Certain features of the invention are not limited, however, to machines for performing this particular operation, but may be embodied with advantage in machines for performing other operations. Also certain features of the invention are not limited to machines which are wholly automatic and certain features of the invention may be embodied in machines for operating upon shoes in which the shoe is held and manipulated by the operator.

The principal object of the present invention is to produce an automatic sole edge trimming machine of improved construction and having an improved mode of operation.

Another object of the invention is to produce an automatic shoe machine of improved construction and mode of operation in which two different tools are employed to operate successively along different parts of the marginal portion of a shoe bottom.

Other objects of the invention are to improve the construction and mode of operation of edge trimming and other shoe machines which are provided with a tool or tools adapted to operate upon the edge of a shoe sole to form or finish the edge.

With the above and other objects in view the features of the invention consist of certain novel and improved constructions, arrangements and combinations of parts hereinafter described and particularly pointed out in the claims, the advantages of which will be readily understood and appreciated by those skilled in the art.

The invention will be readily understood from the accompanying drawings illustrat-

ing the invention in its preferred form and the following detailed description of the constructions therein shown.

In the drawings Figure 1 is a view in front elevation of a machine embodying the invention; Fig. 2 is a view in side elevation of the machine looking from the right; Fig. 3 is a plan view of a portion of the machine; Fig. 4 is a view in side elevation of the edge trimming head of the machine; Fig. 5 is a view similar to Fig. 4 illustrating certain of the parts in different positions; Fig. 6 is a view in front elevation of the edge trimming head; Fig. 7 is a view in vertical section of the edge trimming head taken substantially on the line 7—7 of Fig. 6; Fig. 8 is a view of the edge trimming head partly in front elevation and partly in section taken substantially on the line 8—8 of Fig. 4; Fig. 9 is a view in front elevation partly broken away and partly in section illustrating particularly the driving mechanism; Fig. 10 is a view in vertical section taken substantially on the line 10—10 of Fig. 1; Fig. 11 is a detail plan view illustrating the jack supporting and actuating mechanisms and certain associated parts; Fig. 12 is a detail plan view of a portion of the mechanism shown in Fig. 11; Fig. 13 is a view in side elevation partly in section of a portion of the machine illustrating particularly the jack supporting and actuating mechanisms; and Figs. 14 and 15 are detail plan views partly in section illustrating in different positions certain parts of the stopping mechanism.

In the machine illustrated in the drawings the edge trimming mechanism is fixed in position as regards the transfer of the point of operation about the work and a shoe supporting jack is provided which is movably supported in the machine to enable the shoe to be moved in the direction of feed to transfer the point of operation about the shoe, and transversely of the direction of feed to maintain the edge of the shoe bottom in the proper lateral relation to the edge trimming mechanism and to be tipped and turned to change the position of the shoe with relation to the edge trimming mechanism to compensate for the surface and edge curvatures of the shoe sole. The movement of the shoe to transfer the point of operation about

the shoe is imparted thereto by devices acting on the jack to impart shoe feeding movements to the jack and the position changing movements are imparted to the shoe by devices acting on the jack to impart tipping and turning movements to the jack. Except as changed and modified in embodying the present invention in a machine adapted to trim the edges of shoe soles, 10 the machine has the same general construction, arrangement and mode of operation of parts as the machine illustrated and described in applicant's pending application, Sér. No. 255,209, filed September 21, 1918.

15 The edge trimming mechanism of the machine comprises a rotary cutter shaft 2 mounted in bearings 4 secured in an adjustable carriage 6, and arranged to carry trimming cutters at the lower end thereof. The cutter shaft 2 is driven through intermeshing spiral gears 10 and 12 from a horizontal shaft 8 which constitutes the main shaft of the edge trimming head. The main shaft 8 is journaled in bearings formed in the carriage 6 and is driven from an electric motor indicated at 13 secured to said carriage.

Upon the lower end of the cutter shaft 2 are mounted a cutter 14 for operating about the forepart of the shoe and a cutter 16 30 for operating along the shank. Upon the lower end of the shaft is also mounted a sleeve 18 arranged to slide longitudinally of the shaft and provided with projections extending between the blades of the cutter 35 14 for engagement with the sole of the shoe, as shown in Fig. 7. The downward movement of the sleeve on the shaft is limited by a collar 20, and the sleeve is acted upon by a coiled spring 22 which tends to hold the sleeve in its lowermost position and allows the same to yield upwardly.

To enable a shoe to be located and held in operating position with relation to the trimming cutters, the machine is provided 45 with a work table 24 arranged to engage in the crease between the upper and projecting margin of the sole of the shoe. The work table is secured to an arm 26 on the frame, and is arranged to extend in front 50 of the cutters, as shown clearly in Fig. 6.

The lasted shoe is supported during the edge trimming operation by a jack 28 mounted on the upper end of a spindle 30 supported at its lower end to permit its gyration. The supporting devices for the spindle 30 comprise a wheel 32 rotatably mounted on a stud 34 and connected with the spindle by a gimbal joint. The stud 34 is supported at the forward end of a yoke 36 pivoted to swing in a vertical plane on a second yoke 38. The yoke 38 in turn is pivoted to swing in a horizontal plane on a link-frame 40 carried by and connecting the swinging arms 42 and 44. The forward 65 end of the yoke 36 is held up yieldingly by

means of a coiled spring 46 connected to the yoke 38. The force exerted by this spring, however, is less than the force exerted by gravity on the jack so that the margin of the shoe sole exerts a certain amount of 70 downward pressure on the work table 24 during the trimming operation. The margin of the shoe sole thus rests on the table and the shoe is partially supported thereby.

During the trimming operation the shoe 75 is held at all times at the point of operation by the engagement of the table 24 in the crease between the upper of the shoe and the projecting margin of the sole. Relatively slight vertical movements are 80 imparted to the jack and the shoe by the cooperative action of the spring 46 and the table 24, which serves as a guide for the shoe. The supporting devices for the jack spindle permit the lower end of the spindle to be 85 freely moved horizontally in any direction and also permit the jack to tip freely in any direction about the lower end of the spindle. Tipping and turning movements are 90 imparted to the shoe to position the shoe properly with relation to the operative edge trimming tool as the point of operation is transferred about the shoe. The required tipping movements are imparted to the shoe by devices acting to move the lower end of 95 the jack spindle forwardly and rearwardly and laterally of the machine and the required turning movements are imparted to the shoe by devices acting to rotate the jack 100 spindle. Because of the fact that the shoe 105 is held at all times at the point of operation by the table 24, the tipping and turning movements imparted to the shoe are caused to take place about said table as a 110 fulcrum.

The lower end of the spindle is moved forwardly and rearwardly and laterally in opposite directions to tip the jack, and the spindle is rotated to turn the jack through suitable connections from a series of cams mounted on a cam shaft 48 which, for convenience, will be hereinafter termed the pattern cam shaft.

Forward and rearward movements are 115 imparted to the lower end of the jack spindle by means of a cam roll 50 mounted on a lever 52 pivotally connected to the frame and to the arm 42, the roll being arranged to engage a cam groove in a cam disk 53 mounted on the cam shaft 48. The connections for moving the lower end of 120 the spindle laterally from a cam on the cam shaft 48 comprise a bell crank lever 54, a link 56 connecting a depending portion of the yoke 38 with the bell crank lever, a lever 58 articulated to the frame and to the bell crank lever, and a cam roll 60 carried by the lever 58 and arranged to engage a cam 125 groove formed in the under side of the cam disk 53. The mechanism for rotating the 130

jack spindle comprises a cable 62 passing about the wheel 32 and about a series of guide rolls 64, 66, 68, and 70, a pivoted segment 72 to which one end of the cable is secured, and a weight 74 secured to the other end of the cable. The swinging movements of the segment 72 are produced and controlled by a cam lever 76, one arm of which is connected with the segment 72 by intermeshing gear segments and the other arm of which carries a cam roll 78 arranged to engage a peripheral cam on a cam disk 79 mounted on the cam shaft 48.

The jack spindle is acted upon intermediate its lower end and the jack by mechanism tending yieldingly to swing the jack about the connection between the lower end of the spindle and the wheel 32 toward the rear of the machine. This mechanism comprises a rod 80 connected at its forward end with the jack spindle and acted upon at its rear end by devices including a spring (not illustrated), tending yieldingly to move the rod rearwardly. These devices are arranged to act upon the rod with a variable force and are controlled by movements of the jack spindle during the operation of the machine. This mechanism acts on the jack to maintain the shoe in proper rearward position with the work support 24 engaged in the crease between the upper and the projecting margin of the sole.

The machine illustrated in the drawings is provided with a movable gage indicated at 82 for guiding the shoe to determine the distance at which the shoe is trimmed from the upper and thus to determine the width of the projecting margin of the sole left after the trimming operation. The gage is pivotally mounted at 84 on an arm on the frame of the machine, and is constructed and arranged to extend upwardly from its pivotal point to a point just below the work table 24 so that its upper end will engage the upper of the shoe. The gage actuating devices of the machine operate under normal conditions to hold the gage at all times positively in contact with the upper of the shoe so that the position of the shoe is determined by the gage throughout the operation of the machine to cause the sole to be trimmed off at the proper distance from the upper at all points in the sole margin. The outline engaged by the gage is considerably different in shape from that to which the sole is to be trimmed and the gage is moved to compensate for the differences in shape between these two outlines. The gage engaging contour of the shoe is somewhat irregular in outline, the irregularities in the same being due to variations in the thickness of the upper at different points, to irregularities in the last and to the overlapping of the parts of the upper at certain points. In order that these irregularities may not be reproduced

on the outsole, the gage 82 is actuated to compensate for these irregularities so that the outsole is trimmed to a regular outline.

The gage is also actuated to compensate for certain of the positioning movements imparted to the shoe during the operation. In order that a wider projecting margin may be left on the sole about the forepart of the shoe than along the shank, the gage is advanced in predetermined relation to the feeding movement of the work in passing from the shank to the forepart, in trimming the first side of the shoe, and is retracted in passing from the forepart to the shank on the opposite side of the shoe.

The mechanism for actuating the gage in this manner comprises a rock shaft 86 mounted in bearings in the frame and an eccentric disk 88 secured to the shaft and arranged to engage a downwardly extending arm on the gage. The gage is acted upon by a coiled spring 90 which normally maintains the lower end thereof in contact with the eccentric disk. The shaft 86 is rotated to advance and cause the retraction of the gage by means of a gear segment 92 secured to the rock shaft and an intermeshing gear segment 94 formed on a swinging arm 96 secured to a rock shaft 98. To the rock shaft 98 is secured another arm 100 which carries a roll 102 engaging a contact face formed on the outer end of an arm 104 secured to a vertical shaft 106. To the shaft 106 is secured a second arm 108 upon which is mounted a cam roll 110 engaging a peripheral cam face formed on the cam disk 53.

The mechanism for actuating the jack to impart feeding movements to the shoe comprises a feeding lever 112 and a bar 114 connecting the feeding lever with the forward end of the jack. During the trimming operation the lever 112 is swung toward the left (Fig. 1) to actuate the jack to advance the marginal portion of the shoe past the cutting tool. The lever 112 is pivoted at 115 on the frame and is actuated in the above manner by mechanism comprising a bell crank lever 116 pivotally connected with the feeding lever and pivotally supported by a hanger 118. The hanger in turn is pivotally supported by a lever 120 which will be herein-after termed the fulcrum carrying lever. The lever 116 is swung about the pivotal connection between the hanger 118 and the fulcrum carrying lever to actuate the feeding lever during the operation of the machine by mechanism comprising a lever 122 connected with the lever 116, a bell crank cam lever 124 and a link 126 connecting the cam lever with the lever 122. The cam lever carries a cam roll 128 arranged to engage a cam on the cam disk 79.

The proper trimming of the edge of a shoe sole usually requires the use of a dif-

ferent type of cutter for trimming the forepart of the sole from that which is employed in trimming the shank. In the present machine the cutter 14 is especially constructed for trimming the forepart of the shoe sole, while the cutter 16 is especially constructed for trimming the shank. To enable the cutters 14 and 16 to be moved alternatively into position to trim the sole edge without shifting the position of the jacked shoe or while the shoe remains in operating position with the table 24 engaged in the crease between the upper and the sole edge, mechanism is provided for adjusting the cutter shaft to shift the position of the lower end thereof both vertically and horizontally. The vertical movement brings one or the other of the cutters 14 and 16 into operating position, while the horizontal movement compensates for the difference in diameter of the cutters. In the construction shown the carriage 6 is eccentrically mounted in a bearing in a supporting ring 130, which in turn is adjustably mounted to rotate in a bearing formed by arms 131 on the frame of the machine. To prevent the carriage 6 from turning with the ring 130 and to give certain movements to the cutter shaft during the adjustment of the ring, the carriage is connected with the frame by means of a link 132. To enable the supporting ring 130 to be turned readily, an operating handle 133 is secured thereto.

When the edge trimming operation is started along the shank of a shoe the ring 130 is located in the position shown in Fig. 5, and the cutter 16 is placed in operating position as shown in this figure. When the forepart of the shoe sole is reached the ring 130 is shifted into the position shown in Fig. 4. During this movement of the ring a movement is imparted to the cutter shaft carriage, by virtue of its eccentric mounting, which shifts the lower end of the shaft in a direction perpendicular to the plane of the shoe sole and also in a direction parallel with said plane away from the central portion of the sole to place the cutter 14 in operating position. When the shank of the shoe is reached in trimming the last side of the shoe, the ring 130 is turned back to the position shown in Fig. 5, thereby adjusting the cutter shaft in a manner reverse to that described above to bring the cutter 16 back into operating position. The arms 131 on the frame may be relatively adjusted so that they will exert sufficient friction on the ring 130 to hold the same in adjusted position by means of an adjusting screw 134.

When a shoe is placed in the machine in correct position for starting the sole edge trimming operation, the fulcrum carrying lever 120 is unlocked and this lever and the fulcrum of the lever 116 carried thereby will be adjusted in accordance with the size

of the shoe through the adjustment of the feeding lever. The mechanism for locking the lever 120 in position during the trimming operation comprises a rod 467 pivotally connected at one end with the lever and passing through a pivoted sleeve 468, and a pair of locking levers 470 pivoted to the sleeve and formed with cam-shaped inner ends arranged to engage the rod 467. The outer extremities of the locking levers carry pins 472 entering slots formed in the opposite ends of a cross-bar 473, to the central part of which is pivotally connected a rod 476, preferably including yieldable sections. The rod 476 is joined to the starting treadle 80 of the machine through connections which are arranged to move the rod longitudinally to the right (Fig. 3), and thereby actuate the levers 470 to lock the rod 467 in the sleeve 468 upon starting the machine, and therefore 85 fix the lever 120 in position. The release of the treadle and reverse movement of the rod 476 free the rod 467.

The adjustment of the fulcrum of the lever 116 will time relatively the action 90 of the jack actuating feeding mechanism and the position changing mechanism in accordance with the size of the shoe to be operated upon. With a constant speed of rotation of the pattern cam shaft 48 the adjustment of 95 the fulcrum of the lever 116 would result in variations in the rate of feed of the shoe for different sizes. It is preferred that the shoe shall be fed at a substantially uniform rate regardless of size, and in the 100 present machine the speed of the pattern cam shaft is adjusted in accordance with the size of the shoe to secure a substantially uniform rate of feed. The adjustment of the fulcrum carrying lever produced upon 105 the placing of the shoe in starting position, through a connection, which will later be identified, between said lever and the driving mechanism for the pattern cam shaft, will adjust the speed of said shaft in accordance with the size of the shoe. 110

The edge trimming cutters may be driven continuously from the electric motor. The driving mechanism for the rest of the machine comprises a driving shaft 135 upon which is mounted a fast pulley 136 and a loose pulley 137. The driving shaft carries a bevel gear 138 which meshes with a bevel gear 139 mounted on the upper end of a vertical countershaft 140. Fixed upon the counter shaft 140 is a disk carrying the driving member 141 of a friction clutch, the driven member of which, indicated at 142, is carried by a sleeve 144 loosely mounted on the countershaft. The sleeve 144 also carries a spiral gear 146 meshing with a spiral gear 148 formed on a sleeve 149 mounted on a horizontal counter shaft 150 to rotate therewith. During the sole trimming operation the members 141 and 142 125 130

of the friction clutch are engaged and the countershaft 150 is driven at a speed depending upon the speed of the driving shaft 135.

The pattern cam shaft 48 is driven 5 through a spiral gear 152 journaled on a shaft 154 and meshing with a spiral gear 156 secured to the upper end of the pattern camshaft. The spiral gear 152 is driven through a clutch connection from a bevel gear 158. During the trimming operation the bevel gear 158 is driven through a train of gears 160, 162, 164, 166 and 168 from a sleeve 170, a ratchet clutch (not shown) being interposed between the gear 166 and 10 the gear 168 to allow the gear 166, under certain conditions, to rotate independently of the gear 168 in the same direction in which it is driven from the latter gear. The sleeve 170 is driven through suitable variable 15 speed transmitting mechanism, not shown in drawing, from a countershaft 172 which in turn is driven from the shaft 150 through intermeshing gears 174 and 176. The mechanism for adjusting the variable speed transmitting mechanism intermediate the countershaft 172 and the sleeve 170 is controlled 20 through a link 178 from the fulcrum carrying lever 120.

In starting the machine, the circuit of 30 the electric motor having been previously closed so that the trimming cutters are being rotated, the sleeve 144 is elevated by the operator to engage the members 141 and 142 of the main driving clutch and is held in 35 elevated position by a latch. When a point in the operation of the machine on the shoe is reached at which the operation is to be stopped, this latch is released, the members 40 of the main driving clutch are disengaged and the shaft 150 is stopped by suitable stopping devices.

The mechanism for elevating the sleeve 144 to start the machine comprises a disk 45 186 mounted on a sleeve 188 and connected through intermeshing gear teeth with a sleeve 189 which supports the sleeve 144, a rock shaft 190 mounted in the sleeve 188, connections indicated at 192 including a spring between the sleeve and the rock shaft, 50 for turning the sleeve from the rock shaft, a lock bolt carrier 194 secured to the shaft, a slide 196 mounted in the carrier, a spring 198 acting on the slide, a pin 200 projecting from the slide and engaging in a slot 202 in a fixed bracket, a spring pressed plunger 204 for limiting the movement of the carrier 194, a lever 206 and a link 208 connecting the lever with the slide 196. Fig. 9 shows the parts in the positions which 55 they assume when the machine is at rest. In starting the machine the operator swings the lever 206 downwardly, thereby swinging the carrier 194 in a direction to elevate the sleeve 144 to engage the members of the main driving clutch. The lever 206 is

swung downwardly to start the machine by means of a treadle 210 connected with the lever 206 by a treadle rod 212.

During the trimming operation the carrier 194 is held in position to maintain the 70 members of the main driving clutch in engagement by means of a pivoted latch 214 mounted on the lower end of the carrier and arranged to engage a member 216.

The mechanism for disengaging the latch 75 214 from the catch 216 to stop the trimming operation (see Figs. 14 and 15) comprises an arm 218 mounted to turn loosely on a rock shaft 220, and connected with the latch by a link 219, an arm 222 secured to the 80 rock shaft and arranged to engage the arm 218, a second arm 224 secured to the rock shaft, a second rock shaft 226, an arm 228 secured thereto, links 230 and 232 connecting the arm 224 with the arm 228, and an actuating arm 234 secured to the rock shaft 226 and carrying a cam roll 236 arranged to be engaged by cam projections formed in the periphery of the cam disk 79. The cam disk 79 is formed with three cam projections indicated respectively at 240, 242 and 244 for 85 engagement with the cam roll 236 to swing the arm 234 forwardly and thereby through the connections described to disengage the latch 214 from the catch 216. These cam 90 projections are so placed that the latch will be disengaged from the catch to stop the machine respectively when the forepart of the shoe on the side of the shoe first operated upon is reached, when the shank is reached 100 on the opposite side of the shoe, and when the trimming of the shank on the last side of the shoe is completed.

The sleeve 149 is slidable longitudinally of the shaft 150 and carries the driven member 246 of a slow speed clutch, forming part 105 of the stopping mechanism. The driving member of the clutch indicated at 248 is mounted to turn on the shaft 150 and is driven at relatively slow speed from the countershaft 140 through a train of gears, 250, 252, 254 and 256. The sleeve 149 is normally held in position on the shaft 150 with the members of the slow speed clutch 110 disengaged by means of a spring (not shown). Upon the disengagement of the latch 214 from the catch 216, the members of the main driving clutch are disengaged, and the sleeve 149 is moved longitudinally of the shaft 150 to engage the driven clutch member 115 with the driving clutch member. The slow speed clutch when first engaged acts as a friction brake to slow the shaft 150 down to the speed of the driving member of the clutch, and then acts as a driving clutch 120 to drive the shaft in a forward direction to stopping position. When the shaft arrives at stopping position the sleeve 149 is moved longitudinally of the shaft to disengage the 125 members of the slow speed clutch and the 130

rotation of the shaft is arrested by a suitable brake.

- The mechanism for thus shifting the sleeve 149 comprises an oscillatory lever 258 carrying a cam roll 260 engaging in a cam groove 262 in the sleeve 149 and a lock bolt portion 264 projected from the slide 196 and arranged to engage in a recess in the lever 258 to lock the lever to the lock bolt carrier.
- 10 When the machine is running normally the slide 196 is depressed and the lock bolt portion is disengaged from the recess in the lever 258, allowing the lever to swing idly. Upon the disengagement of the latch 214 from the catch 216, the slide 196 is elevated by the spring 198 and the lock bolt portion operates to lock the slide to the lever 258. The sleeve 149 is then shifted longitudinally of the shaft 150 to engage the members of
- 20 the slow speed clutch, and the carrier 194 is actuated to turn the disk 186 to depress the sleeve 189. During the downward movement of the sleeve 189, said sleeve engages a collar 265 secured in the gear 146 and the sleeve 144 is depressed to disengage the members of the main driving clutch. When the speed of the shaft 150 has been reduced and the shaft has been driven forwardly to stopping position, the sleeve 149 is shifted in the opposite direction to disengage the members of the slow speed clutch and the carrier 194 is swung in the opposite direction to engage the brake.
- 25 The brake comprises a brake disk 266 mounted on the shaft 150 to slide longitudinally of the shaft and arranged to engage a disk 268 secured to the shaft. The brake disk is normally held out of engagement with the disk 268 by a suitable spring (not shown). The brake disk is held from rotation with the shaft 150 and is actuated to engage the disk 268 by means of a lever 270 pivoted at 272. The mechanism for actuating the lever 270 to engage the brake
- 30 comprises a lever 274 pivoted on a shaft 275 and carrying a spring actuated latch 276 arranged to engage a pin 278 on the slide 196. As the lower end of the carrier 194 is swung to the left, (Fig. 9) following the movement of the sleeve 149 to disengage the slow speed clutch, the pin 278 engages the latch 276, the lever 274 is swung with the carrier bringing the hub of the latch 276 into engagement with the lever 270, and the lever 270 is actuated to engage the brake.
- 35

When the machine has been stopped at the conclusion of the trimming operation on the last shank, the operator manipulates the jack to disengage the shoe from the machine.

40 Then while holding the jack away from the machine, the operator throws in a clutch mechanism which operates to drive the pattern cam shaft 48 independently of the shaft 150 to bring the jack to its initial or

45

starting position. When the pattern cam shaft has described substantially a complete revolution from the point at which it started at the beginning of the trimming operation, thereby restoring the jack to starting position, this clutch mechanism is automatically thrown out of operation.

The mechanism for thus driving the pattern cam shaft independently of the shaft 150 to bring the jack to starting position comprises a roll or Horton clutch, the driving member of which, indicated at 280, is secured to the lower end of the shaft 140. This clutch mechanism also comprises a driven member 282, clutch rolls 284, a clutch controlling sleeve 286, a clutch engaging spring 288, and a clutch controlling lever 290 for holding the sleeve 286 in position. The driven member 282 of the Horton clutch is connected by means of clutch dog 291 with a shaft 292 to which is secured a bevel gear 293 meshing with the bevel gear 158. Thus when the Horton clutch is thrown into operation, the spiral gear 152 is rotated through the Horton clutch, the clutch dog 291, the shaft 292, and the bevel gears 293 and 158 to drive the pattern cam shaft 48 independently of the shaft 150. The ratchet clutch intermediate the gears 166 and 168 permits this independent movement of the pattern cam shaft.

The lever 290 is acted upon by a spring pressed plunger 295 which tends to swing the same in a direction to throw in the clutch. During the trimming operation the lever 290 is held in position to maintain the clutch out of operation by means of a pivoted latch 294 arranged to engage the forward end of a bar 296 connected with the lever 290. In throwing the roll clutch into operation the operator swings the latch 294 away from the forward end of the bar 296 allowing the plunger 295 to actuate the lever 290 to throw in the clutch. When the pattern cam shaft has described substantially a complete rotation from the point at which it started at the beginning of the trimming operation, the bar 296 is actuated to swing the lever 290 back to its initial position, thereby throwing out the clutch. The bar 296 is actuated in this manner by the arm 222 which is arranged to engage a shoulder on the bar. The arm 222 is swung rearwardly at the proper time to throw out the clutch by means of a cam roll 298 mounted on an arm 300 secured to the rock shaft 226 and a cam projection 302 formed on the cam disk 79 and arranged to engage said cam roll.

Although the present invention has been illustrated as embodied in an automatic shoe machine, it is to be understood that certain features of the invention may be applied with advantage to non-automatic machines

and that, except as defined in the claims, the invention is not limited to any particular class of machines.

In the machine illustrated in the drawing the mechanisms for supporting and actuating the jack, the mechanism tending yieldingly to swing the jack toward the rear of the machine, the gage for guiding the shoe, and the mechanism for controlling and actuating the same, the mechanism for actuating the jack to impart feeding movements to the shoe, the mechanism for driving the pattern cam shaft 48 during an operation on the shoe, the mechanism for stopping the machine during or at the completion of an operation on the shoe, the mechanism for driving the pattern cam shaft to restore the jack to starting position, and the mechanism for throwing out the latter driving mechanism, with the exception of certain changes pointed out above, have substantially the same construction, arrangement and mode of operation of parts as the corresponding mechanisms illustrated and described in applicant's pending application previously mentioned.

Having explained the nature and object of the invention, and having specifically described the machine embodying the various features of the invention in their preferred forms, what is claimed is:

1. A machine for operating on shoes having, in combination, means for operating on a shoe comprising two different operating tools arranged to act successively along different parts of the bottom margin of the shoe during a single transfer of the point of operation along said margin, a shoe supporting jack, mechanism acting automatically to change the relative positions of the shoe and the operating means to compensate for the surface and edge curvatures of the shoe sole as the point of operation is transferred along the bottom margin of the shoe, and mechanism for moving relatively the jack and tools at an intermediate point in such transfer to locate the tools interchangeably in operating position with relation to the shoe bottom.

2. A machine for operating on shoes having, in combination, means for operating on a shoe comprising two different operating tools arranged to act successively along different parts of the bottom margin of the shoe during a single transfer of the point of operation along said margin, a shoe supporting jack, mechanism acting automatically to change the relative positions of the shoe and operating means to compensate for the surface and edge curvatures of the shoe sole as the point of operation is transferred along the bottom margin of the shoe, and means for moving the tools at an intermediate point in such transfer to locate the same interchangeably in operating position with relation to the shoe bottom.

3. An edge trimming machine having, in combination, an edge trimming cutter, a shoe supporting jack, mechanism for changing the relative positions of the shoe and the trimming cutter to present the shoe properly to the cutter as the point of operation is transferred about the shoe, a movable gage arranged to engage the shoe along a contour having an irregular outline, and automatic means for moving the gage to compensate for the irregularities in the outline engaged by the gage so that the shoe sole is trimmed to a regular outline.

4. An edge trimming machine having, in combination, an edge trimming cutter, a shoe supporting jack, mechanism for changing the relative positions of the shoe and the cutter to present the shoe properly to the cutter as the point of operation is transferred about the shoe, a movable gage for engaging the upper of the shoe along a contour having an irregular outline, and means for moving the gage to compensate for the irregularities in the outline engaged by the gage so that the sole is trimmed to a regular outline.

5. An edge trimming machine having, in combination, two rotary edge trimming cutters, means for rotating the cutters, a shoe supporting jack, mechanism for changing the relative positions of the shoe and the operative cutter to present the shoe properly to the cutter as the point of operation is transferred about the shoe, and means for moving the cutters to locate the same interchangeably in operating position with relation to the shoe sole.

6. An edge trimming machine having, in combination, a rotary cutter shaft, means for driving the shaft, two cutters of different forms mounted on the shaft, a shoe supporting jack, mechanism for changing the relative positions of the shoe and the operative cutter to present the shoe properly to the cutter as the point of operation is transferred about the shoe, and means for adjusting the shaft to locate the cutters interchangeably in operating position relatively to the shoe sole.

7. An edge trimming machine having, in combination, a rotary cutter shaft, means for driving the shaft, two cutters of different forms mounted on the shaft, a shoe supporting jack, mechanism for changing the relative positions of the shoe and the operative cutter to present the shoe properly to the cutter as the point of operation is transferred about the shoe, and means for adjusting the shaft to shift the cutters in a direction perpendicular to the plane of the shoe sole and also in a direction parallel with said plane toward and from the central portion of the sole to locate the cutters interchangeably in operating position.

8. An edge trimming machine having, in

combination, a movable jack, a rotary cutter shaft, means for rotating the shaft, a cutter mounted on the shaft, and a fixed work table arranged to engage in the crease between the upper and the projecting margin of the sole of a shoe and to serve as a fulcrum for the jack in its movement.

9. An edge trimming machine having, in combination, a rotary cutter shaft, means for rotating the shaft, a cutter mounted on the shaft, a fixed work table extending in front of the cutter and arranged to engage in the crease between the upper and the projecting margin of the sole of a shoe, a movable gage arranged below the table to engage the upper of the shoe, and means for moving the gage.

10. A machine for operating on shoes having, in combination, two tools for operating on the edge of a shoe sole, a work table in contact with which the shoe is moved arranged to engage in the crease between the upper and the projecting margin of the sole of the shoe, and means for relatively moving the table and the tools to locate the tools interchangeably in operating position.

11. An edge trimming machine having, in combination, two rotary sole edge trimming cutters, a fixed work table in contact with which the shoe is moved arranged to engage in the crease between the upper and the projecting margin of the sole of the shoe, and means for moving the cutters interchangeably into operating position.

12. An edge trimming machine having, in combination, a rotary cutter shaft, two sole edge trimming cutters mounted on the shaft, a fixed work table in contact with which the shoe is moved arranged to engage in the crease between the upper and the projecting margin of the sole of the shoe, and mechanism for shifting the shaft to locate the cutters interchangeably in operating position.

13. A machine for operating on shoes having, in combination, a tool actuating shaft, two tools arranged to be actuated from the shaft, an adjustable carriage for the shaft and tools, and means for adjusting the carriage to locate the tools interchangeably in operating position comprising a ring in which the carriage is eccentrically mounted to turn relatively to the ring, a bearing in which the ring is rotatably adjustable, and means for controlling the turning movement of the carriage during the adjustment of the ring.

14. A machine for operating on shoes having, in combination, a tool actuating shaft, two tools arranged to be actuated from the shaft, an adjustable carriage for the shaft and tools, and means for adjusting the carriage to locate the tools interchangeably in operating position comprising a ring in which the carriage is eccentrically mounted

to turn relatively to the ring, a bearing in which the ring is rotatably adjustable, and means for preventing rotary movement of the carriage during the adjustment of the ring.

15. A machine for operating on shoes having, in combination, a tool actuating shaft, two tools arranged to be actuated from the shaft, an adjustable carriage for the shaft and tools, and mechanism for adjusting the carriage to locate the tools interchangeably in operating position comprising means for bodily adjusting the carriage, and a link pivotally connected at one end with the carriage and at the other with a point on the frame of the machine.

16. A machine for operating on shoes having, in combination, two tools for operating interchangeably on the marginal portion of a shoe sole, a shoe supporting jack, mechanism for feeding the shoe, mechanism for changing the relative positions of the shoe and the operative tool to present the shoe properly to the tool as the point of operation is transferred about the shoe, means for stopping the feeding and position changing mechanisms at the completion of the operation along the shank on the side of the shoe first operated upon, at the completion of the operation about the forepart and at the completion of the operation on the shoe, and means for shifting the tools to interchange the same when the feeding and position changing mechanisms are stopped at the first two of these points.

17. A machine for operating on shoes having, in combination, two tools for operating interchangeably on the marginal portion of a shoe sole, a shoe supporting jack, mechanism for feeding the shoe, mechanism for changing the relative positions of the shoe and the operative tool to present the shoe properly to the tool as the point of operation is transferred about the shoe, means for stopping the feeding and position changing mechanisms at one or more points before the operation on the shoe is completed, mechanism for shifting the tools to interchange the same when the feeding and position changing mechanisms are stopped at these points, and means for stopping the machine at the completion of the operation.

18. An edge trimming machine having, in combination, a rotary cutter shaft, a cutter mounted on the shaft, a fixed table for engagement in the crease between the upper and the projecting margin of the sole of a shoe and arranged to extend in front of the cutter, a freely movable shoe supporting jack, means acting yieldingly on the jack to maintain the shoe in position with the table engaged in said crease, and mechanism for actuating the jack to tip the shoe about said table as a fulcrum as the point of operation is transferred about the shoe.

19. A machine for operating on shoes having, in combination, a tool for operating on the edge of a shoe sole, a shoe supporting jack, means for imparting lateral movements to the jack, and a fixed work table for engagement in the crease between the upper and the projecting margin of the sole of a shoe, said work table being arranged to extend in front of the tool and causing the lateral movements imparted to the jack to tip the shoe about said work table as a fulcrum to locate the shoe bottom in the proper plane with relation to said tool.

20. An edge trimming machine having, in combination, a rotary cutter shaft, a cutter mounted on the shaft, a fixed work table for engagement in the crease between the upper and the projecting margin of the sole of a shoe and arranged to extend in front of the cutter, a movable gage mounted below the table for engagement with the upper, a shoe supporting jack, mechanism for imparting movements to the jack to determine the position of the shoe with relation to the cutter as the point of operation is transferred about the shoe, and mechanism for actuating and controlling the gage to cause the cutter to trim the sole at a predetermined distance from the upper at all points in the sole margin.

21. In an edge-trimming machine, a plurality of cutters each consisting of a plurality of circumferentially arranged blades and situated about a common axis, and means arranged to move the cutters longitudinally of the axis and transversely thereof.

22. In an edge-trimming machine, a jack, a plurality of cutters rotatable about a common axis for co-operation with the jack, and means arranged to move the cutters longitudinally of the axis to bring one or another opposite the jack and to move said cutters transversely of the axis into and out of operating position.

23. In a shoe machine, a carrier, a plurality of operating devices supported upon the carrier, and an eccentric cooperating with the carrier and movable to bring one or another of the devices into operating position.

24. In a shoe machine, a carrier, a plurality of operating devices supported upon the carrier, motor means for the operating devices supported upon the carrier, and a mounting for the carrier movable to bring one or another of the devices into operating position.

25. In an edge-trimming machine, a carrier, a shaft journaled therein, means for rotating the shaft, a plurality of cutters supported upon the shaft, and an eccentric upon which the carrier is mounted.

26. In an edge-trimming machine, a carrier, a shaft journaled therein, a motor supported upon the carrier and connected to the shaft, a plurality of cutters supported upon

the shaft, and an eccentric upon which the carrier is mounted.

27. In a shoe machine, a carrier, a plurality of operating devices supported upon the carrier, a mounting for the carrier movable to bring one or another of the devices into operating position, means arranged to move the mounting, and means for controlling the movement of the carrier.

28. In an edge-trimming machine, a carrier, a shaft journaled therein, means for rotating the shaft, a plurality of cutters supported upon the shaft, a mounting for the carrier, means arranged to turn the mounting, and connections between the carrier and a relatively fixed point.

29. In a shoe machine, a movable shoe support, a rotatable device for operating upon the edge of a shoe bottom, and a contact member in proximity to the point of operation about which the support may be turned throughout the operation to compensate for the surface and edge curvatures of the shoe bottom, and present the edge of the shoe bottom to the operating device.

30. In a shoe machine, a shoe-support pivoted to permit gyration, a device for operating upon the edge of a shoe-bottom, and a fixed member arranged to engage the crease of the shoe during the movement of the support.

31. In an edge-trimming machine, a gyroscopic jack, a rotatable edge-trimming cutter, and a contact member furnishing a fulcrum about which the jacked shoe may move for presentation to the cutter of the edge in the movement of the jack.

32. In a shoe machine, a movable shoe support, a device for operating upon the edge of a shoe bottom, a contact member in proximity to the point of operation about which the support may be turned to compensate for the surface and edge curvatures of the shoe bottom and present the edge of the shoe bottom to the operating device, and a gage contacting with the shoe in its travel.

33. In a shoe machine, a movable shoe-support, a device for operating upon the edge of a shoe-bottom, a member for contact with the shoe, means for moving the supported shoe in contact with said member to maintain a predetermined relation to the edge of the operating device, a gage contacting with the shoe-upper to determine the extension of the edge, said shoe upper having projections from a regular outline, and means for moving the gage to compensate for the projections.

34. An edge trimming machine having, in combination, an edge trimming cutter, a shoe supporting jack, mechanism for determining the relative positions of the shoe and the cutter as the point of operation is transferred about the shoe, a movable gage arranged to engage the shoe, and automatic

mechanism for moving the gage to compensate for the positioning movements imparted to the shoe so that the shoe is trimmed to a regular outline.

5 35. A machine for operating upon shoes having, in combination, two operating tools, and a shoe supporting jack relatively movable to transfer the point of operation about a shoe supported upon the jack, mechanism

10 for changing the relative positions of the shoe and the operative tool to present the shoe properly to the tool as the point of operation is transferred about the shoe, mechanism acting automatically to stop the relative

15 movement of the tools and jack at one or more predetermined points in the operation on the shoe, means for shifting the tools to locate the same interchangeably in operating position when the relative movement of the jack and tools is stopped at these points, and mechanism for stopping the machine at the completion of the operation on the shoe.

36. A machine for operating on shoes having, in combination, a rotary edge trimming cutter, a shoe supporting jack, a guide in proximity to the point of operation past which the shoe is moved and which determines the distance from the shoe upper at

30 which the cutter trims the sole, means for moving the jack to transfer the point of operation around the sole of a shoe supported on the jack, and mechanism acting automatically to change the relative positions of the cutter and shoe to compensate for the surface and edge curvatures of the shoe sole as the point of operation is transferred around the shoe.

37. A machine for operating on shoes having, in combination, a tool for operating on the edge of a shoe sole, a shoe supporting jack, a guide in proximity to the point of operation past which the shoe is moved and which determines the distance from the shoe

40 upper at which the tool acts on the sole, means for moving the jack to transfer the point of operation around the sole of a shoe supported on the jack, and means for moving the jack about the guide as a fulcrum as

45 the point of operation is transferred around the shoe to change the relative positions of

the tool and shoe to compensate for the surface and edge curvatures of the shoe sole.

38. A machine for operating on shoes having, in combination, a sole edge trimming cutter, a shoe supporting jack, a movable gage contacting with the upper of the shoe at a distance from the crease and determining the position of the shoe with relation to the cutter as the point of operation is transferred around the shoe, means for moving the jack to transfer the point of operation around the sole of a shoe supported upon the jack, and means for moving the gage during such transfer to regulate the distance from the upper at which the cutter trims the sole.

39. A machine for operating on shoes having, in combination, a forepart edge tool, a shank edge tool, a shoe supporting jack longitudinally movable and rotatable to transfer the point of operation of a tool around the sole of a shoe supported on the jack, a guide in proximity to the point of operation past which the shoe is moved and which determines the distance from the shoe upper at which the tools act on the sole, means for relatively moving the tools and jack to locate the tools interchangeably in operating position with relation to the sole of a shoe supported on the jack, and mechanism acting automatically while the shank tool is operative to move the jack to transfer the point of operation along the shank of the shoe, and while the forepart tool is operative to transfer the point of operation from the shank portion on one side to the shank portion on the other side.

40. A machine for operating on shoes having, in combination, a forepart edge tool, a shank edge tool, a shoe supporting jack longitudinally movable and rotatable to transfer the point of operation around the sole of a shoe supported on the jack, a guide in proximity to the point of operation past which the shoe is moved and which determines the distance from the shoe upper at which the tools act on the sole, and means for moving the tools interchangeably into operative position.

LAURENCE E. TOPHAM.
